UNITED STATES PATENT OFFICE.

JOSEPH GAWRONSKI, OF SEATTLE, WASHINGTON.

SHOE-CAP PROTECTOR.

Application filed February 14, 1923. Serial No. 619,001.

To all whom it may concern:

Be it known that I, JOSEPH GAWRONSKI, a citizen of Poland, residing at Seattle, in the county of King, State of Washington, have 5 invented certain new and useful Improvements in Shoe-Cap Protectors, of which the following is a specification.

This invention relates to devices for protecting the front and sides of the toe of a 10 shoe from undue wear and has special reference to shoes for miners, loggers, hunters, military men, children and others. The invention further refers to the art of making said protecting device. The objects of the 15 invention are to provide such a device which will be thick and high enough to provide an effective wearing surface in front of and on each side of the toe of the shoe; which will not extend over the cap or otherwise make 20 the shoe too stiff for comfort; and which will materially increase the life of the shoe. In order to accomplish these objects it is necessary to form the protecting strip so 25 that its central portion is longer than its edges and the object of the improvement in the art is to shape and manipulate this strip so as to accomplish this purpose.

I attain these and other objects by the 30 devices, forms and arrangements illustrated in the accompanying drawings in which Fig. 1 is a vertical section of a shoe provided with my device; Fig. 2 is a plan view thereof; Fig. 3 is a plan of the strip of leather from 35 which the protector is made; Fig. 4 is a section of the front portion of the protector, as shaped; and Fig. 5 is a side elevation thereof. Similar numerals of reference refer to similar parts throughout the several views.

This device comprises a thick piece of sole 40 leather 1, shaped, scraped, and bent so as to form a thick pad or wearing surface 2, extending up from the sole 3 to a point substantially level with the top of the toe cap 4 in front, and of gradually lessening height 45 on each side; said piece 1 being scraped thin along one portion 5 in order to lie smoothly under the insole 6, and being held in place between the soles by any suitable means. But it will be observed that, in 50 order to make this piece 1 of the correct shape on the shoe, inclined backward from the bend 7 at the sole 3 to its top edge 8

(Fig. 4) it is evident that the bent part 7, forming the lower edge of the wearing surface 2, must be slightly longer than the top 55 edge 8 and that the edge of the part 5 must also be shorter than the said bent part 7. It is further evident that the top edge 8 cannot, in practice, be cut or slashed in order to shorten it but must be of one continuous 60 piece of leather. Therefore the piece 1 must be of a shape somewhat similar to that shown in Fig. 3, depending in detail on the shape and size of the shoe toe to be protected. This shape is such that the lay-out of the 65 leather is roughly of crescent shape, the inner line of the crescent being the top edge 8 of the protector, the line of the bent part 7 being substantially the center line of the crescent, and the part of the crescent outward 70 from the line 7 being scraped thin to fit between the soles and being cut or slit at points 9 therein, as needed, in order to permit the horns of the crescent to be folded back into the reversed position. 75

In practice, then, I form a piece of sole leather of such a shape, slicing or scraping the part 5 thin and cutting serrations 9 therein, as needed. Then, after proper soaking and softening, the center part of the 80 part 5 is fastened in place and the wearing pad 2 is bent up tightly against the shoe toe; then one side and then the other side are bent and pressed into position and the part 5 is secured in place in the usual way at various points therealong, thus holding the said 85 protector tightly against the shoe toe. After this the sole 3 is fastened in place, being made long enough to extend beyond the bend 7 of the protector. 90

Thus it will be seen that I have provided an effective wearing surface in front of and on each side of the toe of the shoe, and that said surface is made to fit the shoe as above described. I am aware that others have 95 taken a single thickness of shoe leather and have carved it out so that a thickness similar to an extra sole extends around the lower portion of the shoe toe, but this protection is of no value for the rough usage of shoes in many industries, and to extend their device to a practical depth would be impossible as no leather known would be of sufficient thickness for this purpose, therefore it na 100

become necessary to invent the method or art of making the above described protectors.

Having described my invention, what I claim is:—

5 A shoe cap protector comprising a strip of leather adapted to be bent in front of, under and around the sides of a shoe toe and secured thereto, the upper edge of said protector, as thus bent, being shorter in

length than the central part thereof, where-
by the bending of the protector to pass the
same under the shoe toe places the upper
edge of the protector under tension, thus
causing said protector to be held in contact
with the shoe toe and preventing the same 15
from sagging in front thereof.

JOSEPH GAWRONSKI.
